UNITED STATES PATENT OFFICE.

CHARLES A. CASE, OF TRENTON, NEW JERSEY.

CARRIAGE FOR TRACK-CABLES.

No. 806,637.

Specification of Letters Patent.

Patented Dec. 5, 1905.

Application filed April 16, 1904. Serial No. 208,392.

To all whom it may concern:

Be it known that I, CHARLES A. CASE, a citizen of the United States, and a resident of Trenton, in the county of Mercer and State of New Jersey, have invented certain new and useful Improvements in Carriages for Track-Cables, of which the following is a specification.

This application comprises an improvement of my invention forming the subject-matter of United States Letters Patent No. 720,781, dated February 17, 1903, and relates to a carriage for track-cables, tram-rails, and the like; and its specific object is the production of a carriage with a gripping device by means of which it can be automatically locked and unlocked to a traction-rope for propulsion without slipping on either practically horizontal or inclined tram-rails or track-cables.

The organization of the invention comprises a carriage with a gripping device actuated by the load suspended from the carriage, the load causing the gripping device to be clamped to a traction-rope with the same force whether on a horizontal or inclined track.

The invention is further characterized by means that prevent the gripping device disengaging from the traction-rope in the event of any jarring or springing of the carriage on its said tram-rail or track-cable.

In the accompanying drawings, Figure 1 represents an elevation of the carriage with a portion of its tram-rail, supporting-rail, and guide-rail in a station or terminal with the jaws of the gripping device open. Fig. 2 is 35 shows an end view and partial section of Fig. 1. Fig. 2^a shows a partial section on the line $x^2 x^2$ of Fig. 6, slightly modified. Fig. 2^b shows a partial section on the line $x^4 x^4$ of Fig. 2^a. Fig. 3 represents a partial section of the 40 carriage as on the line $x x$ of Fig. 4 with the jaws of the gripping device closed. Fig. 4 is a partial section of Fig. 3 on the line $x' x'$. Fig. 5 represents a top view of Fig. 3 with a portion broken away. Fig. 6 represents a 45 front view of the carriage with the jaws of the gripping device open. Fig. 7 shows a partial end view of Fig. 6. Fig. 8 is a section of Fig. 6 on the line $x^2 x^2$. Fig. 9 is a partial side view of the movable jaw of the 50 gripping device. Fig. 10 is a partial section of the stationary jaw of the gripping device on the line $x^3 x^3$ of Fig. 6.

Referring to the drawings, the invention is shown to consist of the carriage A, carrying 55 a gripping device having the jaws $m m'$, and a hanger B, with its load, consisting in this

case of the bucket C. In Figs. 1 and 2 the carriage is shown with its supports in a station or terminal, and they consist of a tram-rail D, with bent-up ends D², carried on a support D'. Above the tram-rail is fixed the guide-rail H, with its bent-up ends H' and its support H², and below the tram-rail the supporting-rail G, with its ends bent down at G², is carried on the support G'. The track-cable R extends from the ends of the tram-rail in the usual manner.

The hanger B carries the braces b b', to which latter are bolted the brackets B', that support the pins b² for the roller, F. A bracket E', 70 connected to the side plate of the carriage by the rivets e, supports the pin E, from which the hanger B is suspended.

The carriage comprises the wheels A', capable of turning on the axles A², which latter 75 are journaled to inner plates H and generally secured thereto with pins h' and extend through the side plates H'. The plates H are connected at their central portions by the guide-block I with the rivets i, which clamp 80 the ears i² and the said plates together. A cover-plate J, with ears j, extends between the side plates H', and rivets j² j⁴ clamp the said cover-plate to the side plates. The cover-plate extends to the wheels A' and protects 85 the mechanism of the invention from snow, ice, and foreign substances. Bolts K K' extend through the elongated openings r in the guide-block I and clamp together the side plates H' and sleeves k² on the bolts, which 90 latter constitute separators between the said side plates and also constitute rollers on the bolts.

The gripping device and its appurtenances consist of the stationary jaw m and movable 95 jaw m' , the latter being pivoted on the adjustable pivot N. Legs m^3 extend from the stationary jaw m , and rivets j⁴ clamp the upper portions of the said jaw, as well as the cover-plate J, to one of the side plates H', while rivets j⁵ clamp the said legs to the side plate.

The movable jaw m' has extending below its pivot N the lower leg m^2 , which latter carries a pin m^8 , from which extend the links m^3 , that carry the pin m^4 with roller m^5 . The pin 105 m^4 and its roller extend through the guide or guide-opening I' in the guide-block I. Links m^6 swing from the pin J', supported in a bearing j³, extending from the cover-plate J, and connect at their free ends with the pin m^4 . 110 The traction-rope P is shown between the jaws.

The guide-opening I' at its lower end contains for a short distance the vertical walls i^3 for securely holding in place the pin m^4 , with its roller m^5 .

5 The pivot N is eccentrically supported in the plugs O, that fit in the hubs m^7 of the stationary jaws m , and the ends O' of the plugs are generally hexagonal in shape. Screws O² in the hubs m^7 hold the plugs in different positions. By turning the hexagonal ends O' of the plugs the pivot N throws the movable jaw m' different distances from the stationary jaw m , thereby enabling the adjustment of the jaws for gripping traction-ropes of different diameters. In Figs. 2^a and 2^b, which show a slight modification of a portion of the carriage, one of the wheels is shown at A³ loosely fitting the bushing 1, which latter has the oil-holes 2. The inner plates 12 carry the supports 5, and the side plates 3 have the slots 4 for the supports 5, that are flattened at the sides 6 to enable them to move in the said slots and prevent their turning. The axle 7 has the collar 8 and the nut 9 for clamping together the said axle, supports 5, and bushing 1. An oil-hole 10 in the axle connects with grooves 11 and the holes 2.

To operate the invention, the carriage is moved onto the tram-rail D in a station or 30 terminal, the rollers F being by so doing carried on the supporting-rail G, and the wheels A' of the carriage are thereby moved down, the slots h allowing the axles A², with the wheels, to descend from the normal positions 35 they occupy when the rollers F are not supported on the tram-rail. By virtue of this downward movement of the wheels A' the inner plates H, with the guide-block I, are also moved down, and the pin m^4 , with its roller 40 m^5 , is forced from the lower portion of the guide-opening I' to the upper portion thereof, and the connections between said pin and the movable jaw m' of the gripping device causes the latter to open and allows the traction-rope 45 P to fall in place. The carriage is moved from the tram-rail D, and as soon as the rollers F are clear of the supporting-rail G the weight of the bucket pulls down the sides H', so that the crowns of the slots h nearly bear 50 on the ends of the axles A² or in the modified form on the supports 5. The pins m^4 , with their rollers m^5 , then find a good bearing in the lower portion of the guide-opening I' between the parallel walls i^3 , and thus maintain 55 the jaws m m' tightly gripped to the traction-rope P.

Having described my invention, I claim—

1. In a carriage the combination of wheels and sides, a gripping device connected up with 60 the carriage, means to operate the said device, the said means actuated by moving the wheels of the carriage, in lines at right angles to a plane passing through the axial lines of their axles.

65 2. In a carriage the combination of a grip-

ping device, side plates having slots, inner plates adjacent to the side plates, axles connected with the inner plates and capable of moving in the slots in the side plates, in directions perpendicular to a plane passing through the axial lines of the axles, and wheels 70 on the axle.

3. In a carriage the combination of wheels and sides therefor, a guide-block connected up with the carriage, a gripping device for a traction-rope connected to the carriage, a pin guided by the guide-block, means to locate the pin in different positions in the guide-block to lock and unlock the gripping device with its traction-rope, connections between 80 the pin and the said gripping device.

4. In a carriage the combination of a gripping device for a traction-rope, a guide-block connected up with the carriage, a pin arranged to move in a guide in the guide-block, parallel vertical walls in the guide-block for the pin, connections between the pin and the gripping device.

5. In a carriage the combination of a gripping device for a traction-rope, a movable jaw 90 in the said gripping device, a guide-block connected up with the carriage, a pin arranged to move in a guide in the guide-block, connections between the said pin and the movable jaw, means to move the pin to different positions in the guide of the guide-block.

6. In a carriage the combination of sides, a gripping device for a traction-rope on the carriage, a movable jaw in the said gripping device, a cover-plate connecting the said sides, links swinging from the cover-plate, a guide-block having a guide-opening connected up with the carriage, a pin capable of moving in the said guide-opening, and the pin connected with the said links, other links connecting the pin with the movable jaw, means to move the pin in the guide-opening to different positions therein, and actuate the movable jaw of the gripping device.

7. In a carriage the combination of sides, 110 and wheels movable relatively to said sides, a movable jaw of a gripping device pivoted to the carriage, a pin supported in a bearing rigidly connected to the said sides, linked connections between the movable jaw and the said pin, means to move the said linked connections and thereby the movable jaw, by the said movement of the wheels relatively to the sides 115 of the carriage.

8. In a carriage the combination of wheels and sides therefor; a movable jaw of a gripping device pivoted to the carriage; a pin supported in a bearing rigidly connected to the said sides; links between one end of the movable jaw and the said pin; a second pin connecting the links; a guide-block arranged to move with the wheels, and having a guide-opening for the said second pin, to guide the latter when the wheels are moving relatively 120 to the sides.

9. In a carriage the combination of sides having slots, inner plates for the carriage adjacent to the sides, a guide-block supported by the inner plates, a stationary jaw of a gripping device fastened to the sides, a movable jaw pivoted to the said stationary jaw, a guide-block having a guide-opening fastened to the inner plates, a pin passing through the said opening, a bearing connected to the sides of the carriage, a pin supported in said bearing, linked connections between the two said pins, and linked connections between the pin in the guide-opening and the movable jaw, wheels for the carriage, axles for the wheels moving with inner plates and in the slots of the sides.

10. In a carriage the combination of wheels and sides therefor, a stationary jaw of a gripping device connected to one of the said sides, movable plugs connected up with the said stationary jaw, a pivot eccentrically supported in the plugs, a movable jaw of the gripping device supported on the said pivot.

11. In a carriage the combination of sides, inner plates adjacent to the sides, the plates and sides arranged to move relatively to each other, wheels for the carriage connected up to move with the inner plates, a guide-block connected to the inner plates and having a guide-opening, a gripping device with a mov-

able jaw connected to the carriage, a pin in the said guide-opening, linked connections between the pin and the end of the movable jaw, a second pin supported in a bearing connected with the sides of the carriage, linked connections between the two pins, a seat formed in the guide-opening for the pin passing therethrough when the jaws are closed, and sides of the opening extending above said seat to prevent lateral movement of the pin when in its seat, the continuation of said sides in the opening formed, to allow a vertical and lateral movement of the pin in the said guide-opening, and thereby open the jaws.

12. In a carriage the combination of side plates having slots, and inner plates adjacent to the side plates, supports held in the inner plates and capable of moving in the slots in the side plates, an axle carried in a pair of the supports, a bushing on the axle, means to clamp the pair of supports and said bushing together, a wheel turning on the bushing.

Signed at New York, in the county of New York and State of New York, this 22d day of March, A. D. 1904.

CHARLES A. CASE.
